UNITED STATES PATENT OFFICE.

WILLIAM P. HENSZEY, OF PHILADELPHIA, PENNSYLVANIA, ASSIGNOR TO
BURNHAM, WILLIAMS & CO., OF SAME PLACE.

LOCOMOTIVE.

SPECIFICATION forming part of Letters Patent No. 660,483, dated October 23, 1900.

Application filed January 4, 1900. Serial No. 377. (No model.)

To all whom it may concern:

Be it known that I, WILLIAM P. HENSZEY, a citizen of the United States, residing in Philadelphia, Pennsylvania, have invented certain improvements in Locomotives, of which the following is a specification.

The object of my invention is to improve the construction of locomotives known as the "double-end type," which usually have a very long wheel-base and in which the wheels must be mounted, so that they will readily turn the ordinary curves.

In carrying out my invention I utilize two locomotive-engines of the ordinary type coupled back to back, so that while a long wheel-base is obtained there is no more difficulty in passing around curves than by the use of the locomotive of the ordinary type. Furthermore, I so couple the throttle-valve levers and reversing-levers that the levers of both engines can be operated by one engine-driver at his post on either locomotive.

In the accompanying drawings, Figure 1 is a side view of a double-end locomotive, illustrating my invention. Fig. 2 is a diagram view showing the wheel-base. Fig. 3 is a longitudinal sectional view through the cab of the locomotive, showing one of the reversing-levers thrown forward. Fig. 4 is a section on the line 4 4, Fig. 3. Fig. 5 is a sectional plan view on the line 5 5, Fig. 3; and Fig. 6 is a sectional view on the line 6 6, Fig. 5.

A A' are two locomotives, in the present instance shown as of the six-wheel freight type.

B B' are the cabs of the two locomotives. The locomotives are placed back to back, as clearly illustrated in Fig. 1, and the hood b, attached to the roof of the cab B', overlaps the roof of the cab B.

D D' are the two boilers of the locomotives of the usual type, and E E' are the frames. Secured to the frames are the buffer-boxes e e', in which are mounted the buffers f f', held rigidly by the compressed backing. Directly under the buffers is a draw-bar G, secured to the frame E by coupling-pins g g', which are set in the frame, as clearly illustrated in Fig. 6.

H H' are the throttle-valve levers. H² is a swiveled connecting-bar situated directly un-

der the footboard of the locomotive. Each end of the connecting-bar is in the form of a ball, and the balls are adapted to sockets h h' on each section of the locomotive, as clearly illustrated in Figs. 5 and 6. On the bar are 55 arms h² h³. The arm h² is connected to the throttle-valve lever H by a rod h⁴, and the arm h³ is connected to one arm of the throttle-valve lever h' by an arm h⁵, so that if one throttle-valve lever is moved by the engine-driver motion will be imparted to the other throttle-valve lever through the rods h⁴ h⁵ and connecting-bar H².

I I' are the reversing-levers of the locomotives, each situated in the usual position on its respective locomotive, and in the present instance these levers are operated by screws i i', adapted to swiveled bearings i i' in brackets I² I³, the screws being adapted to nuts 65 i⁴ i⁵, swiveled to the levers I I', respectively. It will be understood that other mechanism than the screws i i' may be utilized for operating the levers, depending upon the style of engine desired.

I I' are mounted loosely on bent shafts J J', respectively, which are adapted to bearings j j in the frames of the locomotives. Secured to the shafts are arms K K', which can be coupled to the reversing-levers I I' by 75 latches k k', pivoted to the arms and adapted to openings k² in the levers I I'. The arms K K' are connected to the reversing-rods L L', respectively, as illustrated in Fig. 3.

The shafts J J' are bent so as to clear the 80 coupling head and pins, as clearly shown in Fig. 4. Extending from each bent shaft J J' are arms J² J³, connected together by a connecting-rod J⁴, so that the movement of one shaft will be imparted to the other, and when 85 the reversing-lever is shifted for the forward movement of one engine the valve motion of the other engine will be shifted to backward motion, and when the engine-driver is at his post on one engine the reversing-lever of the 90 95 100

other engine is uncoupled from its arm. This locking mechanism can be used to lock the lever, being operated in its set positions.

I preferably make the joints between the extensions J^2 J^3 and the connecting-rod J^4 swivel-joints, so as to allow for the lateral movement of the locomotive in passing around curves. In the present instance I fork each element and mount between the forks a block m and couple the arms J^2 and J^3 to their respective blocks by cross-pins n and couple the rod J^4 to the blocks by vertical pins n' , so that while the motion of one shaft will be imparted to the other through the connecting-rod J^4 the swivels will allow free movement of the locomotive without interfering with the reversing mechanism.

By the above description it will be readily seen that I can couple two single locomotives of the ordinary type back to back, so that one engine-driver and one fireman can operate two engines and that both engines will be thus under control of a single driver. It will be understood, however, that the engines are not to be used singly except in extreme cases, as they are supposed to be permanently coupled together, and the shafts J J' and connecting-rod J^4 , as well as the swiveled bar H^2 , are permanent parts of the locomotive.

Locomotives of the type above described are used quite extensively on certain roads where heavy loads are hauled and where the grades are difficult, and it is essential that the wheel-base be such that the locomotive will readily accommodate itself to the curves and will be under the control of a single engine-driver.

I claim as my invention—

1. The combination of two complete and independent locomotives flexibly coupled back to back, the operating mechanism of one locomotive flexibly connected to the operating mechanism of the other locomotive, whereby one engine-driver can control the two locomotives, substantially as described.

2. The combination of two complete and independent locomotives flexibly coupled back to back, reversing mechanism on each locomotive, means whereby the two reversing mechanisms are flexibly connected so that when the reversing mechanism of one locomotive is moved in one direction the reversing mechanism on the other locomotive is reversed, substantially as described.

3. The combination of two complete and independent locomotives flexibly coupled back to back, throttle-valves on each locomotive, a connecting-bar flexibly connected to the two throttle-valve levers, so that both throttle-valves will be under the control of one engine-driver, substantially as described.

4. The combination of two complete and independent locomotives flexibly coupled back to back, throttle-valves on each locomotive, levers therefor, a connecting-bar adapted to swivel-joints on each locomotive and having arms connected to the two levers, substantially as described.

5. The combination of two locomotives coupled back to back, a shaft adapted to bearings on each locomotive, an arm on each shaft, one arm connected to the reversing mechanism of one locomotive, the arm of the other shaft connected to the reversing mechanism of the other locomotive, independent reversing-levers on each locomotive, and means for coupling one or other of the reversing-levers to their respective arms, so that when the engine-driver is at his post on one locomotive the reversing-lever of the other locomotive can be thrown out of engagement with the arm connected to the reversing mechanism, substantially as described.

6. The combination of two locomotives arranged back to back, a long coupling-link connecting the two locomotives, bent shafts pivoted to their respective locomotives on a line with the coupling-pins, extensions on said shafts, a rod coupling the two extensions together, said rod being swiveled to the extensions, reversing-levers connected to the said shafts, an extensible bar having heads adapted to sockets on each locomotive, and throttle-valve levers connected to the bar, substantially as described.

In testimony whereof I have signed my name to this specification in the presence of two subscribing witnesses.

WM. P. HENSZEY.
